VENTILATOR FOR CONVEYANCES

**Frank N. Gould and David R. Henderson,
Minneapolis, Minn.**

Application May 12, 1933, Serial No. 670,675

2 Claims. (Cl. 98—2)

Our invention relates to ventilators and particularly to ventilators for conveyances, such as automobiles, railroad cars, street cars, air craft etc.

5 An object of our invention is to provide a ventilator for conveyances whereby motion of the conveyance causes exhausting of air from the interior of the conveyance with the result that fresh air will enter the interior through windows, cracks or other openings.

15 Another object is to provide such a ventilator including power driven means for use in exhausting air when the conveyance is not in motion or for use to boost the exhaust of air when the conveyance is in motion.

Still another object is to provide such a ventilator which will be operative when installed in any location in which it will be subjected to a stream of air moving relatively to itself.

20 Yet another object is to provide such a ventilator, the various parts of which can be controlled by control elements located at a distance therefrom.

A still further and more specific object is to provide such a ventilator wherein suction for exhausting air from the interior of a vehicle or conveyance is produced in a venturi by means of air drawn through the venturi by motion of the vehicle or conveyance through the air.

30 These and other objects and advantages of the present invention will more fully appear from the following description, made in connection with the accompanying drawing, wherein like reference characters refer to the same or similar parts throughout the various views, and, in which,

Fig. 1 is a horizontal sectional view taken along the line 1—1 of Fig. 2, as indicated by the arrows;

Fig. 2 is a vertical sectional view taken along the line 2—2 of Fig. 1, as indicated by the arrows;

40 Fig. 3 is a vertical sectional view taken along the line 3—3 of Fig. 2, as indicated by the arrows.

Fig. 4 is a vertical sectional view taken along the line 4—4 of Fig. 1, as indicated by the arrows;

45 Fig. 5 is an electrical connection diagram of the electrical operating and control circuits of our ventilator.

Referring to the drawing, our ventilator includes a generally rectangular casing 10 formed of sheet metal or other suitable material. This casing includes a top plate 10a, a bottom plate 10b, a front plate 10c, a rear plate 10d, and side plates 10e. The casing 10 is preferably secured to the lower side of the floor F of a conveyance

so as to be carried by and located beneath the floor F.

A rearwardly converging truncated conical conduit 11 is secured at its forward end to portions of the front plate 10c defining a circular aperture. A second conduit 12, having a rear portion of uniform diameter and a forwardly diverging, truncated conical forward portion, is secured at its rear end to portions of the rear plate 10d defining a circular aperture. The second conduit 12 is axially aligned with the first conduit 11 and the forwardmost portion of the second conduit 12 is disposed about the rearmost portion of the first conduit 11 in annularly spaced relationship thereto. The conduits 11 and 12 cooperate to form a straight flow venturi extending through the casing 10 and having an inlet and an outlet both open to the space surrounding the casing 10. The most constricted portion of the venturi is situated at the rear end of the conduit 11 and hence, when air is passing through the venturi from front to rear, a partial vacuum is set up in this constricted portion tending to suck air into the interior of the venturi through the annular space between the conduits 11 and 12 and eject this air with the discharge of the venturi.

A conduit 13 extends from the interior of the casing 10 through suitable apertures in the top plate 10a of the casing and the floor F to a point just above the floor F at which point it is secured to a register 14.

A centrifugal blower 15, having an electric motor 16 to drive the same, is disposed within the casing 10 with its intake conduit 15a extending upwardly through suitable apertures in the top plate 10a and the floor F and secured to the register 14. The discharge 15b of the blower 15 is open to the interior of the casing 10.

The space above the floor F is in communication with the interior of the casing 10 both through the conduit 13 and through the blower 15.

A shutter 17, of generally circular shape and formed of sheet material, has at its lower portion an ear 17a which is pivotally mounted on the medial part of the lower portion of the front plate 10c by means of a screw 17b. Stops 18 and 19, mounted on the front plate 10c, are provided to limit the movement of the shutter 17. The shutter 17 is so arranged that it, when in one of its extreme positions, will cover the forward end of the conduit 11 of the venturi to prevent entrance of air into the venturi. When the shutter 17 is in the other one of its extreme 45 50 55

positions the front end of the venturi is completely open to receive air. The shutter 17 is obviously so mounted that it will fall from any intermediate position to one or the other of its extreme positions.

5 A cover plate 20 is supported forward of the front plate 10c in parallel and spaced relation thereto by means of suitable extensions of the side and top plates of the casing 10.

A shaft 21 is journaled in the cover plate 20, 10 the front plate 10c and a cross piece 22 which is secured at its ends to the side plates 10e a substantial distance rearwardly of the front plate 10c and above the forward end of conduit 11. At 15 a point between the cover plate 20 and the front plate 10c an arm 23 is mounted on the shaft 21 in depending relation thereto.

A link 24 is pivotally connected at its upper end to the free end of the arm 23 and at its lower end to a point adjacent the pivot screw 20 17b as shown in Fig. 3. A pair of solenoids 25 are mounted at opposite sides of and somewhat below the shaft 21 rearward of the front plate 10c and forward of the crosspiece 22. Each of the solenoids 25 has therewithin a plunger or 25 armature 26, the inner end of which extends inwardly of the solenoid and is connected through a spring wire link 27 to the lower end of a lever 28 which is mounted on and depends from the shaft 21 at a point between the front plate 10c 30 and the crosspiece 22.

One terminal of the blower motor 16, of each of the solenoids 25, and of a source of electrical energy, such as the battery B, is connected to a common conductor 29 as shown in the electrical 35 connection diagram of Fig. 5. The common conductor 29 may be the metal frame of the conveyance. The remaining terminal of the battery B is connected to the remaining terminal of the blower motor 16 through a switch 30 and is connected selectively to the remaining terminal of one or the other of the solenoids 25 through a spring centered, normally open, single pole, double throw switch 31 and wires 32 as shown in Fig. 5. The wires 32 are cut at their point of 40 entrance to the casing 10 and the circuits carried thereby are completed through terminal studs 32a which are insulated from the casing 10 and to one of which each of the wires 32 is connected.

Operation

50 When the conveyance is in motion and the shutter 17 is in its open position air will flow through first the conduit 11 and then the conduit 12 of the venturi in the direction indicated by 55 the arrows in Fig. 2. In the constricted portion of the venturi at the rear end of the conduit 11 the air will have its maximum velocity of flow and its lowest pressure. The partial vacuum in this low pressure zone will cause sucking of air from the interior of the casing 10 into the interior 60 of the venturi through the annular space between the conduits 11 and 12 of the venturi and, of course, air will be drawn from the interior of the conveyance through the conduit 13 into the interior of the casing 10. Some air will also be drawn from the interior of the conveyance into the interior of the casing 10 through the blower 15. The above action will be continuous as long as the conveyance is in motion with the result 65 that air adjacent the floor of the conveyance will be constantly withdrawn and exhausted through the venturi. The air withdrawn will naturally be replaced by air from the upper portions of the interior of the conveyance and this air will in turn be replaced by air entering 70

through the windows, cracks or other air inlets of the conveyance or through hot air heating devices in the conveyance.

When the conveyance is not in motion the withdrawal of air may be continued by closing the switch 30 whereby the blower motor 16 will operate the blower 15 to deliver air from the interior of the conveyance to the interior of the casing from whence it will escape to the outside through the venturi. The blower may also be 10 used to augment the effects of the venturi while the conveyance is in motion. When the conveyance is not in motion and the direction of the wind is such as to tend to blow dust, exhaust gases, etc. through the ventilator into the 15 interior of the conveyance, the blower may be used to prevent entrance of these undesirable elements.

The shutter 17 at the front end of the venturi may be opened or closed by momentarily 20 operating the switch 31 to energize the corresponding one of the solenoids 25. When the shutter is to be operated, the solenoid at the side opposite the position of the shutter is energized to attract its armature and hence to swing 25 the lever 28 and the arm 23 in a direction away from the shutter. This action bows the spring wire link 24 to place the same under spring tension and pulls the shutter upwardly from one 30 extreme position to its dead center position relative to its pivot 17b after which the spring wire link will straighten to force the shutter to its other extreme position. The shutter functions to either prevent or permit movement of air through the venturi and hence to prevent or permit induced ventilation by means of the venturi. The primary purpose of the shutter is to prevent 35 the entrance of mud, snow, dust etc. into the venturi when it is not desired to use the ventilator.

The control switches 30 and 31 for the blower motor 16 and the shutter operating solenoids 25 may, of course, be installed in a location conveniently accessible to the operator of the conveyance thus providing complete remote control 40 of the ventilator.

It will be noted that the lower end of the space between the front plate 10c and the cover plate 20 is open to permit mud etc. to drop from this space instead of accumulating therein.

It is apparent that the shutter may be 50 remotely operated by means other than electrical means and it is also apparent that the upper ends of the conduit 13 and of the intake 15a of the blower may be provided with closable registers if 55 desired.

The interior of the casing 10 may be lined with sheets of heat insulating material (not shown) to prevent or minimize condensation of moisture within the casing.

The action of our ventilator to draw cold air from just above the floor of the conveyance causes 60 warmer air from above to descend to the floor and thus prevents the accumulation of cold air near the floor while causing a continuous circulation 65 of air in the conveyance.

The removal of moist air from the interior of the conveyance by our ventilator will prevent frosting of the windows of the conveyance in cold weather.

Ventilation by removing air from the interior of a conveyance as by means of our ventilator is not attended by drafts since it is not necessary for air entering the conveyance to enter entirely at 70 one point or to enter as a blast of air.

It is apparent that we have invented a novel, efficient, effective and readily controllable form of ventilator for conveyances whereby movement of such conveyances through the air will produce ventilation of the conveyances and wherein means is provided for producing ventilation when such conveyances are not in motion.

It will, of course, be understood that various changes may be made in the form, details, arrangement and proportions of the various parts without departing from the scope of the present invention.

What is claimed is:—

1. A ventilator for conveyances comprising a casing adapted to be mounted externally of a conveyance, an air inlet tube mounted in the top wall of said casing for communication with the interior of a conveyance and running downwardly to a point adjacent but spaced from the bottom of the casing and located rearwardly from the forward end of said casing, a truncated conical first conduit mounted in the forward part of said casing and having an open forward end at the forward end of said casing, said first conduit converging rearwardly and its rear end being in slightly rearwardly spaced relation from said tube, a second conduit coaxially aligned with said first conduit and mounted in the rear portion of said casing, said second conduit including a forward truncated conical part which converges

rearwardly and a rear part which joins the rear end of said forward part and is open at its rear end through the rear wall of said casing, the forward portion of said forward truncated conical part of said second conduit surrounding the rearmost portion of said first conduit in annular relation and being disposed somewhat rearwardly from said tube.

2. A ventilator for conveyances comprising a casing adapted to be attached to the floor boards of a conveyance below the same and having a forward end exposed to the air as the conveyance moves therethrough and a rear end opposed to said forward end, an open ended truncated conical first conduit mounted in said forward end, converging rearwardly and terminating short of said rear end, a second open ended conduit mounted in said rear end and having a diverging forward portion, the forward part of which surrounds the rear part of said first conduit in spaced relation, a tube passing through the top of said casing to communicate with the interior of the conveyance and terminating at its lower end within said casing and a blower having an intake mouth passing through the top of said casing for communication with the interior of the conveyance and having a discharge outlet within said casing.
